UNITED STATES PATENT OFFICE.

JOSEPH ELMER, OF CHICAGO, ILLINOIS.

PROCESS OF CIRCULATING HOT WATER IN A HOT-WATER HEATING SYSTEM.

1,185,892.

Specification of Letters Patent. Patented June 6, 1916.

Application filed November 18, 1912. Serial No. 732,030.

To all whom it may concern:

Be it known that I, JOSEPH ELMER, a citizen of the United States, residing at Chicago, in the county of Cook and State of Illinois, have invented a certain new and useful Improvement in Processes of Circulating Hot Water in a Hot-Water Heating System, of which the following is a specification.

10 The objects of the invention are to cause a more uniform distribution of heated water in the radiator, thereby economizing the heat energy, and to prevent freezing of the water when the water level within a radiator

15 falls below the intercommunicating passageway at the top of the radiator sections.

An apparatus by which the invention may be carried into effect, is illustrated in the accompanying drawings, wherein:

20 Figure 1 is a diagrammatic view showing the hot water system. Fig. 2 is an enlarged view showing one form of reducing device separate from the radiator. Fig. 3 is an enlarged view in section with parts broken 25 away showing the inlet end of one of the radiators.

Like numerals refer to like parts throughout the several figures.

For purposes of illustration, I have shown 30 a hot water heating system in diagrammatic form, consisting of a boiler 1 and a series of radiators 2; the boiler 1 is connected with the radiators 2 by means of the inlet pipe 3 and a return pipe 4. An expansion tank 5 is connected with the system by means of a pipe 6 and is provided with an overflow pipe 7, which may lead to a drain or storage tank as desired. Each radiator 2 is made up of a 35 series of sections 8, 8^a, 8^b, etc., connected together at the top and bottom, as illustrated.

In the ordinary construction of a hot water heating system it is difficult to secure 45 thorough circulation of hot water within the radiator. The failure to procure a thorough circulation prevents the radiator from being efficient and where but one stream of water flows through a radiator it is liable to freeze up in cold weather.

If a stream of hot water is allowed to flow 50 through the top of the radiator the tendency of the flow and movement of the water is first through the top and then down the end section, thereby causing the heat energy to short circuit the bottom portions of the radiator, and affecting adversely the transmission of heat within the bottom portions of

the radiator, as a consequence of which the water therein becomes inert. The radiator is more liable to freeze when the water circulates in this manner, for the reason that if 60 the level of the water falls below the top openings within the radiator the flow therethrough will stop. If a full stream of water is allowed to flow through the bottom of a radiator the tendency of the flow and outward movement of the water is directly through the bottom from inlet to outlet, which affects adversely the flow of water 65 through the top portions of the radiator.

I find by practical tests that in order to 70 create thorough circulation and uniform distribution of heated water in all portions of the radiator a free outward movement of all of the water contained in the radiator sections must be secured, thus permitting the 75 hot water to follow this outward movement of the cold or used water, and this cannot be properly done by the use of but one flow, either through the top or bottom of the 80 radiator.

In carrying out the process I provide 85 means for introducing the hot water into the radiator at the bottom thereof, and then dividing the moving body of water into two portions or currents, one of relatively large volume and the other of relatively small volume. In this manner the larger or main current is directed upwardly through the first of the radiator sections and downwardly through the remaining sections, the 90 auxiliary portion or current is directed at an angle with the main current and along the bottom of the radiator, as herein shown. There is placed between the first section 8, and the second section 8^a, a reducing device 95 provided with a small central opening 10. The water leaves the radiator through the return pipe 4 and returns to the boiler 1. I have shown in the drawings a particular construction for the purposes of illustration 100 in order to carry out the process and make my invention clear.

Its use and operation is as follows. When the system is started up, the boiler, pipes and radiators are filled with cold water. 105 The fire in the furnace then heats the water in the boiler; this expands the water and causes it to become lighter, thereby creating an unbalanced state in the system; the hot water rises to the top of the boiler, and the cold water in the system, being heavier, moves downward into the bottom of the 110

boiler through the return pipe 4 and presses the hot water up out of the boiler 1 through the inlet pipe 3 and through the inner portions of the radiators. By reason of 5 the reducing device 9, which divides the water entering from the inlet pipe 3, into two currents, the main current is pressed up the section 8 of the radiator and the smaller current is pressed through the opening 10 in the reducing device 9. The small current of water that is pressed through the opening 10 disturbs the water at the bottom portions of the various sections, 8^a, and 8^b, and causes an outward movement 10 of the water therein toward the return outlet pipe 4, by reason that the water leaving down the return pipe 4 is pressing the water therethrough and at the same time drawing therefrom. The water at the top of the 15 radiator sections, due to the disturbed state and outward movement of the water within the bottom of the sections, moves evenly downward in the sections and follows the outward moving water through the return 20 pipe 4, thus insuring the hot water from the section 8, easy access to the remaining sections of the radiator and establishing a continuous flow therethrough and through 25 the return pipe 4 back to the boiler 1. 30 It will further be seen that when operation first takes place the hot water follows the cold water through the radiator sections, and thereafter it continues to follow the used water through the radiators so long as 35 a proper fire is maintained in the boiler.

The reducing device 10 herein shown can be used to produce the described method of circulating hot water in old systems, at a small expense. The reducing device is made to pass into the bottom inlet opening of 40 the radiator and it is wedged into the mouth of the bottom communicating nipple on the supply side of the radiator. I find that when the method of circulation is used in old plants the radiator operates much more 45 efficiently and it saves in maintenance. I further find that new plants may be installed at a much less expense.

Having thus described my invention I claim:

The method of circulating hot water through a radiator of the type disclosed, which consists of dividing the moving body of water, on the supply side of the radiator, into two currents, one of relatively large 55 volume and the other of relatively small volume, directing the current of larger volume upwardly through the first of the radiator sections and downwardly through the remaining sections, and directing the current of smaller volume through the radiator at the bottom thereof and in the direction of the outlet.

In testimony whereof I affix my signature in the presence of two witnesses this 65 12th day of November, 1912.

JOSEPH ELGER.
